UNITED STATES PATENT OFFICE.

HERBERT B. TAYLOR, OF EAST ORANGE, NEW JERSEY, ASSIGNOR TO
ADVANCE SIGNAL COMPANY, OF NEWARK, NEW JERSEY, A COR-
PORATION OF NEW JERSEY.

ELECTRIC SIGNALING SYSTEM.

SPECIFICATION forming part of Letters Patent No. 793,244, dated June 27, 1905.

Application filed September 1, 1904. Serial No. 223,023.

To all whom it may concern:

Be it known that I, HERBERT B. TAYLOR, a citizen of the United States, residing at East Orange, Essex county, State of New Jersey, 5 have invented a new and useful Electric Block-Signaling System, of which the following is a specification.

My invention relates to electric signaling systems for railways employing track-circuits 10 and adapted to be automatically controlled by conditions in said circuits, such as presence of trains or cars on the track, broken rails, &c.

My invention also relates to the system of signaling known as the "block system," in 15 which the track is divided into a number of blocks or circuits each of which is provided with its own signal or signals for indicating in advance the condition of the block or circuit protected thereby.

20 The objects of my invention are to provide a system of the above character which shall be positive and certain in operation under all conditions of traffic and weather, to provide a system in which the signals shall have a normal danger position, to provide a system in 25 which the signals are electrically locked in either danger or safety position requiring appropriate conditions in the circuits to cause the electric locking means to be released and 30 to move the signal to the normal danger or to the safety position, to provide normally closed and energized signal-circuits and also normally closed and energized rail-circuits, and means for keeping the signal-controlling circuits closed during movements of the signals 35 from one position to another.

The means for the accomplishment of these and other objects will fully appear in the following detailed description and be more particularly pointed out in the claims.

Figure 1 is a diagrammatic view of a portion of a railway equipped with my invention and illustrating the various rail and signal circuits. Fig. 2 is a similar view of one of 45 the signal-stations shown in Fig. 1, but on a larger scale for purposes of chain illustration. Fig. 3 is a view similar to Fig. 2, showing the use of modified form of signal.

A railway equipped with my invention is divided in the usual manner into a series of 50 blocks or track-sections, (illustrated on the drawings by the reference-letters *a b c d*.) The rails *a' a²*, *b' b²*, and *c' c²* of each of these sections are insulated from the rails of adjoining sections, as indicated by the reference-letter 55 *i*, so as to form separate track-circuits. Near the advance end of each block or at any convenient distance therefrom for indicating to the engineer of an oncoming train the condition of the advance section are the signal- 60 stations I II III, &c.

I and D indicate, respectively, home and distant signals for each block. While I have shown in the drawings my system as applied to a railway equipped with both home and 65 distant signals, I desire it to be understood that one signal only may be used for each block without departing from the invention. One instance of such a modification is shown in Fig. 3. The signals may be of any suitable 70 construction, such as semaphore arms or disks, as desired, and may be operated by any suitable mechanism. Preferably I employ the signal-operating mechanism disclosed in Letters Patent No. 646,714, granted to me April 75 13, 1900.

Each of the track-circuits is energized by a battery 1 or other suitable source of current. As the several circuits required for controlling the signals are similar for each section, 80 a description of one of them will be sufficient. The battery or other source of current 1 is connected to each of the rails of a section, as shown. At the opposite end of the section a relay 2 is also connected to the rails of each 85 section. It will thus be seen that each section forms a normally closed track-circuit from one side of the battery 1, through one rail *b'*, to and through the relay 2, to the other rail *b²*, and back to the other side of the battery 1. 90 Each relay 2 controls a double-tongued switch with tongues 3 and 4. The function of the switch 4 will be hereinafter described. It will be understood that the relay 2 operates both tongues 3 and switch 4 simultaneously. The 95 tongue 3 normally makes contact at 3^a to close

a circuit through a connection 5 to a common conducting-wire 6. (This common conducting-wire 6 extends throughout the length of the track to form a return-circuit for the several connections.) From this conducting-wire 6 the circuit referred to passes through a connection 7 to another relay 8 of the next rearward signal-station, through the same and back through connection 9 to the circuit-breaker 3. This circuit just described is energized by a battery 10 or other source of current. Relay 8 operates a double-tongued circuit-closer having tongues 11 and 12. The tongue 11 controls the signal-operating circuit from the signal-battery 13, through the connections 14, and either 15 or 16 16^a, connection 17, signal-switch 18, connection 19, signal magnet-coil 20, connections 21 22, back to battery 13, and also from signal-switch 18, connections 23, signal-motor 24, connection 22, back to battery 13. The other tongue 12 of relay 8 controls a circuit which operates a relay 25 at the rearward signal-station and includes a source of current 26 for energizing said relay 25. This circuit is from battery 26, connection 27, relay 25 of the rearward station, connection 28, common wire 6, connection 29, tongue 12, contact 12^a, back to battery 26.

30 Relay 25 operates a circuit-closer 30, which, with another circuit-closer 38, controls a circuit from signal-switch contact 18^a through connection 31, circuit-closer 38, connection 32, circuit-closer 30, connection 33, signal-switch 34 of distant signal D, connection 35 to magnet-coil 36 of distant signal D, connections 37 and 22, and battery 13.

35 Circuit-closer 38 is one member of a double-tongued circuit-closer having tongues 38 40, 39, which are operated together by a relay 40. This relay is energized by a source of current 41, and the circuit thereof is from battery 41, connection 42, switch-contacts 43, connection 44, relay 40 at the signal-station in advance, connection 45, common wire 6, connection 46, back to battery 41. Circuit-closer 39 controls the circuit from battery 13, through 44, contact 39^a, tongue 39, connection 16 16^a, circuit-closer 11, connection 17, and thence 50 through signal-switch 18, as before described. Contacts 43 are controlled by distant-signal switch 34, which is provided with a blade 34^x, insulated from blade 34, and which bridges contacts 43 when said switch is moved by the 55 movement of distant signal D.

60 It will be understood that, as set forth in my patent hereinbefore mentioned, the signal-switches 18 and 34 are mechanically operated by signals H and D, respectively, to move from one set of contacts to the other. Switch 18 in the normal danger position of signal H makes contact with contacts 18^a and 18^b and in the safety position of signal H moves over to make contact with contacts 18^c and 18^d. 65 Contact 18^e is connected with connection 48,

which leads from contact 4^a of switch 4 to coil 49 of the signal-magnet of signal H, and contact 18^d is connected with connection 31. Switch 18 is provided with an extension 18^x, insulated, as shown, from the main switch-blade 18. This extension-piece in the safety-position of the signal H bridges contacts 18^e and 18^f. Contact 18^e is connected with contact 18^b by connection 18^k, and contact 18^f is connected with contact 34^b of signal-switch 34 75 by a connection 50.

70 Switch 34 of signal D in the normal danger position of that signal makes contact at 34^a with connection 35 and also makes contact at 34^b with connection 50, leading to contact 18^f 80 of the switch of signal H. In the safety position of signal D switch 34 is moved over to bridge contacts 43, as above described, and also makes contact with 34^e.

85 Switches 4, 18, and 34 are so constructed as to make what may be termed "following contacts"—that is, in moving from one position to another there is no break in the circuit, but the new contacts are made before the old ones are broken. This secures 90 steadiness of operation and relieves the sources of current from sudden fluctuations.

95 With the above description of the various parts of the system its operation may now be described. It will be understood under normal conditions all the signals are in danger position and are electrically locked in said position by their magnet-coils in similar manner to my patent hereinbefore mentioned, requiring the proper conditions to be present 100 in the track or rail circuits before they are moved to indicate "safety." All the circuits, both signal and track circuits, are closed and energized. Referring to Fig. 1 of the drawings, the signal-stations indicating the conditions of blocks b, c, and d are designated for 105 convenient reference by the numerals I, II, and III, respectively. Each station is provided with home and distant signals for said blocks, (indicated as H', H², or H³, and D', D², or D³, respectively.) It will be understood that the direction of travel of a train or car upon the system as illustrated is from right to left, as shown by the arrow. In normal condition, with no train or car on any of the sections, the circuits will be as follows: from the battery 13 of signal-station I, through connections 14 15, switch 4, contact 4^a, connection 48, magnet-coil 49 of signal H', connections 21 22, back to the battery 13. Magnet-coil 49 may be a high-resistance coil, and the 115 effect of the current circulating therein, as will be understood from my patent herein referred to, is to electrically lock the signal H' in the normal danger position. As the 120 home and distant signal of each station are mechanically interlocked in any well-known manner, when the home signal is in danger position the distant signal is also held in danger position until the home signal drops to 125

130

"safety." The distant signal is then in condition to drop when its circuits are properly controlled. If now a train or car enter block *b*, the wheels and axles of the same will bridge the rails of said block and short-circuit relay 2 of signal-station II. This relay thereby becomes deenergized, and switch 4 moves over to contact 4^b. The circuit now passes from the battery 13, through connections 14 15, switch 4, contact 4^b, connections 16^a, circuit-closer 11, contact 11^a, connection 17, through signal-switch 18 to contact 18^a, connection 19, coil 20 of signal H², which may be of relatively low resistance and which operates to electrically clutch the signal H² with the motor. The circuit also passes from connection 17 and switch-blade 18 to contact 18^b, thence through connection 23, motor 24, connection 22, back to battery 13. The motor being thus energized operates to shift the signal H² to safety position. This, as will be understood, will occur if the relay 8 of station II be energized to hold its circuit-closer 11 on contact 11^a, keeping the circuit through 16 and 17 closed. If block *c*, however, be occupied or the rail-circuit therethrough be interrupted by a broken or displaced rail or otherwise, the signal H² will not be operated to indicate "safety," but will remain in danger position. The movement of signal H² to safety position also moves switch-blade 18 over to the contacts 18^a 18^b 18^c 18^d. Thereupon the circuit passes from signal-switch 18 to contact 18^a, connection 48, signal-coil 49, and connections 21 22 back to battery 13, thus energizing signal-coil 49 and locking signal H² in safety position by the same means as locked it in danger position. The circuit also passes from the signal-switch 18 to contact 18^d through connection 31, circuit-closer 38, connection 32, circuit-closer 30, connection 33 to the signal-switch 34 of the distant signal D², thence through connection 35, coil 36 (which may be of relatively low resistance) of said distant-signal connections 37 and 22 back to the battery 13. The circuit also passes from the signal-switch 34 through connection 50 to contact 18^e, switch-extension 18^x, contact 18^e, connection 18^f, contact 18^b, and through connection 23, motor 24, back to the battery 13. The current circulating in coil 36 of signal D² and motor 24 operates to move the signal D² to safety position, the effect of the coil 36 being to electrically clutch said signal with the motor. The movement of signal D² also moves switch-blade 34, whereupon the circuit passes from said switch-blade to contact 34^e through connection 51, signal-coils 52 and 36 in series, connections 37 and 22 back to the battery 13. Coil 52 is of relatively high resistance, and being thus energized acts to lock signal D² in shifted or safety position. In moving to its shifted position the member 34^x of switch 34 bridges contacts 43. This completes the circuit from battery 41 through said contacts 43 and switch member 34^x, connection 44, and relay 40 at signal-station III. This relay 40 then becomes energized and operates the double-tongued circuit-closer 38 39 at station III. The tongue 39 makes contact at 39^a, and the tongue 38 breaks contact at 38^a, so that the circuit from battery 13 of signal-station III will be from said battery, connection 14, contact 39^a, tongue 39, connections 16, 16^a, and 17, switch-blade 18, through the low-resistance coil 20 and motor 24, as before described, to move the signal H² at station III to safety position and lock it there. By these means the signals at consecutive stations are interlocked, the distant signal of a rearward station always giving the same indication as will be found at the home signal of the station in advance. It will be seen that the presence of a train or car in section *b* deenergizes relay 8 at station I, this relay being controlled, as before explained, by the circuit-breaker 3 of relay 2 at station II. Thus the home signal H² cannot be operated, but remains in normal danger position, and locked in that position, the current from battery 13 at station I circulating through the connections 14 15, switch 4, connection 48, and coil 49, and connections 21 and 22, since the circuit through connections 16^a 17 is broken at contact 11^a as soon as the train is on the said section *b*. In addition to this the train on the section *b* also controls the distant signal D of the station in rear of station I. This will more readily appear if the train be supposed to be on section *c*, when, as above explained, the home signal H² at station II will be locked in its normal danger position and cannot be operated, and distant signal D² at station I would also be locked in its normal danger position. This latter results from the fact that the train in section *c* by deenergizing relay 8 at station II breaks the circuit at contact 12^a of battery 26 at that station, thereby deenergizing relay 25 at station I, breaking the circuit through connections 32 and 33, which operate said distant signal D² and station I. Thus it will be seen that by my system as herein described the train automatically signals in advance and also in rear. The presence of a train on section *b*, for instance, operates the home and distant signals H² and D² at station II, causing said signals to be set to "safety" if both sections *c* and *d* are clear. If, however, section *c* be clear and section *d* be occupied or its track-circuit interrupted or deranged by accident, then relay 8 at station III will be deenergized, breaking the circuit at contacts 11^a and 12^a. The breaking of the circuit at 12^a deenergizes relay 25 at station II, thereby breaking the circuit at 30^a, which operates distant signal D², so that D² cannot be operated, but will remain locked in danger position. Thus the engineer of the train in section *b* will on approaching station II get a clear signal for the home section *c*, (signal H² being operated,) but a danger sig-

be moved to the third position S'' . The circuit through contacts 38^a and 30^b is dependent upon relays 40 and 25, respectively. Relay 40 is energized by battery 41 of the signal-station in rear, the circuit of this battery being through connection 42, contacts 43, connection 44, relay 40, connection 45, common wire 6, connection 46, back to battery 41. In the normal danger position of the signal at the rearward station switch-blade 18^x will not close contacts 43, and relay 40 will therefore not be energized, so that the circuit through contact 38^a will be closed. This circuit, however, is also controlled by circuit-closer 30^x, which is operated by relay 25. Relay 25 is energized by battery 26 at the station in advance, the circuit being from battery 26, through connection 27, relay 25, connection 28, common wire 6, connection 29, circuit-closer 12, contact 12^a, back to battery 26. Circuit-closer 12 is in the circuit of relay 25 of the rearward station, and this relay is in turn dependent upon relay 8 of the station in advance, relay 8 being in turn dependent upon the track-circuit second in advance. If, therefore, two sections in advance be clear, signal S will be operated by the circuit through circuit-closer 38 and 30^x to move to third position S'' . Switch-blade 18 then moves to contact 18^d and away from contact 18^a, while switch-blade 18^x still bridges contacts 43. The circuit is then as follows: from switch-blade 18, contact 18^d, connections 71 48 60, circuit-closer 30, connections 61 62, signal-coils 49 and 20 in series, connection 63, back to battery 13, thus locking the signal S in third position S'' . This circuit is also dependent upon relay 25, which is in turn dependent upon relay 8 at the station in advance. This system, it will be seen, operates in all respects the same as the double-signal system previously described, the signals at adjacent stations being interlocked by means of the switch-blade 18^x. It will be apparent that the presence of a train upon a section signals in advance and in rear and that two blocks in advance are indicated by the signal.

It will be seen from the above description that the track-circuits are normally energized and that the signal-circuits are constantly energized, except when a train or car is partly on one track-section and partly on the adjacent track-section, during which interval the signal-circuits are deenergized, permitting the counterweights to return the signals to their normal danger position, whereupon the signal-circuits become energized to maintain the signals in their normal danger position—that is to say, the signal-circuits are not broken during the movement of the signal from danger position to “safety.”

With other signal systems with which I am acquainted it frequently happens that both home and distant signals at a station may indicate "safety," but on arriving at the next station

tion in advance the home signal will indicate "danger," thus contradicting the signal previously given. This cannot happen with my system. If the distant block be occupied, the 5 distant signal at the home station will indicate this condition a block in advance, and no contradictory signals will result.

The switches being so constructed that in passing from one contact to another the circuit is never broken, there is merely transition from one circuit to the other. Thus both the signal and rail circuits are normally closed and energized. This results in steadiness of 10 operation and prevents jumping of the signals and also keeps the action of the batteries or other sources of current from deterioration which would result from open circuits and secures quick battery action. The signals being electrically held or locked by means 15 of their signal-coils in either position is also an important feature of advantage, especially in winter-time, when the semaphore-arms become weighted by accumulations of snow or ice and overbalance the counterweights, thus 20 tending to drop and give a false indication of "safety," or the counterweights may become displaced or broken, allowing the signal-arms to drop. My invention thus provides a signal system having great certainty of 25 operation and reliability and enables the engineer of a train to receive timely and confirmatory warnings of the condition of advance sections.

Having thus described my invention, what I claim as new, and desire to secure by Letters 30 Patent, is—

1. A signal system comprising signals normally indicating danger, normally closed and energized signal-operating circuits, said circuits operating to maintain the signals in 35 either danger or safety position, and normally closed track-circuits for controlling the signal-circuits.

2. A signal system, comprising signals having normal danger position, signal-circuits for 40 operating said signals, normally energized track-circuits, relays in the track-circuits, and devices operated by said relays for controlling the signal-circuits and maintaining said circuits closed when the signals are in normal position, throughout their movements from normal to safety position and in the safety position.

3. A signal system comprising a plurality of 45 normally closed track-circuits, a normal danger-signal for indicating the condition of advance track-circuits, normally closed and energized signal-circuits for controlling and operating said signal, and switch devices and circuit-closers operated by the track-circuits for 50 controlling said signal-circuits.

4. A signal system comprising normal danger-signals, normally closed and energized circuits for operating said signals, normally energized track-circuits for controlling the signals, and a following contact-switch in 55

the signal-circuits, said switch controlled by the track-circuits.

5. A signal system comprising normal danger-signals, circuits energized as described for operating said signals, normally energized 70 track-circuits for controlling the signal-circuits, a plurality of following contact-switches in and controlled by the signal-circuits.

6. A signal system comprising normally closed track-circuits, normal danger-signals, 75 signal-circuits for controlling said signals, said signal-circuits controlled by the track-circuits and arranged to lock the signals in danger or safety position and relock the signals on return from safety to danger position. 80

7. A signal system comprising a plurality of track-circuits, a normal danger-signal for each track-circuit, each signal indicating the condition of a plurality of advance track-circuits, signal-circuits for controlling the signals, said 85 signal-circuits controlled by the track-circuits and operating to retain the signals in normal danger position.

8. A signal system comprising a plurality of normally energized track-circuits, normal danger home and distant signals for indicating the condition of advance track-circuits, normally energized signal-circuits for operating said signals, and means for operating a rearward distant signal and an advance home signal, said means being controlled by an advance track-circuit. 90

9. A signal system comprising a plurality of normally energized track-circuits, normal danger home and distant signals for indicating the condition of advance track-circuits, normally energized signal-circuits for operating said signals, means controlled by a distant signal for operating the next home signal in advance. 100

10. A signal system comprising a plurality of normally energized track-circuits, a signal comprising separate home and distant signal devices for indicating the condition of a plurality of advance track-circuits, signal-circuits normally energized and closed for operating said signal devices, switches for controlling the signal-circuits, the switch of a distant signal device controlling the signal-circuit of the home-signal device of the signal next in advance, said signal devices having a normal position of danger. 110

11. A signal system comprising a plurality of normally closed track-circuits, electromagnetic devices in said circuits, signals for indicating the condition of advance track-circuits, signal-circuits for controlling said signals, electromagnetic devices in said signal-circuits, said electromagnetic devices operating to hold the signals in either danger or safety position, 120 switches and circuit-closers operated by the track and signal circuits for controlling said signals. 125

12. A signal system comprising a plurality of normally closed track-circuits, a signal for 130

indicating in advance the condition of each track-circuit, signal-circuits for operating the signals, electromagnetic devices in the signal-circuits for holding the signal in either danger or safety position, switches operated by the track-circuits for controlling the signal-circuits and switches operated by the signal-circuits and controlling the same.

13. A signal system comprising a plurality of track-circuits, home and distant signals for each track-circuit, signal-circuits for operating the signals, a switch operated by each track-circuit, a switch operated by each signal-circuit, electromagnetic devices controlled by the signal-switches for locking each signal in danger or safety position, said signal-circuits controlled by the track-circuit-operated switch.

14. A signal system comprising a plurality of normally closed track-circuits, home and distant signals for each track-circuit, signal-circuits for operating the signals, a switch operated by each track-circuit, a switch operated by each signal-circuit, electromagnetic devices controlled by the signal-switches for locking each signal in danger or safety posi-

tion, said signal-circuits controlled by the track-circuit-operated switches, the electromagnetic signal-operating devices of the home signal of an advance block controlled by the 30 distant signal of the block in rear.

15. A signal system comprising a plurality of track-sections, track-circuits for such sections, normal danger-signals for indicating the condition of advance track-sections, closed 35 and energized signal-circuits for controlling said signals, electromagnetic devices connected to the rails of adjoining track-sections for controlling said signals.

16. A signal system comprising a plurality 40 of track-sections, normally closed track-circuits for said sections, signals for indicating the condition of advance track-sections, closed signal-circuits for controlling said signals and electromagnetic devices connected to the rails 45 of adjoining track-sections for controlling the signals and locking the same in any of their positions.
